Veeder-Root Incorporated, a corporation of
Connecticut

Application July 5, 1932, Serial No. 620,822

31 Claims. (Cl. 235—144)

My invention relates to counters.

It has among its objects to provide an improved counter, and, more particularly, an improved counter of the internal transfer pinion type. A further object of my invention is to provide an improved and accurate counter of this type having positive locking mechanism and cooperating resetting means for resetting the several units while the locking mechanism continues to lock the latter. A still further object of my invention is to provide such an improved mechanism including the above features and especially adapted to use as a trip section in the odometer of a combined speedometer and odometer, while also having an improved structure and improved means for connecting and mounting the several parts in a single unit forming the trip section, and for operatively mounting the latter in the odometer. These and other objects and advantages of my improved construction will, however, hereinafter more fully appear.

In the accompanying drawings, I have shown for purposes of illustration, one embodiment which my invention may assume in practice.

In these drawings,—

Figure 1 is an elevation of a combined speedometer and odometer embodying my improved trip section and mounted in a portion of a dash, with a trip section resetting member shown in exposed position beneath the dash to facilitate illustration;

Fig. 2 is an enlarged elevation partially in section of the trip section and its mounting, drive and resetting means, with certain portions shown in section to facilitate illustration;

Fig. 3 is an end elevation of the trip section structure shown in Fig. 2 as it would appear from the driving end thereof when in a speedometer casing, the latter being shown in dotted lines and certain of the mechanism inside the trip section also being indicated in dotted lines;

Fig. 4 is a still further enlarged view of the counter portion of the trip section, certain of the parts being shown in section on line 4—4 of Fig. 3;

Fig. 5 is an elevation of the opposite end of the trip section;

Fig. 6 is a section on line 6—6 of Fig. 4;

Fig. 7 is a section on line 7—7 of Fig. 4, i. e. looking in the opposite direction from Figure 6;

Fig. 8 is an edge view of the transfer pinion carrying partition plate shown in Figure 7;

Fig. 9 is an enlarged end view of the transfer pinion shown in Figure 7;

Fig. 10 is a top plan view of that pinion;

Fig. 11 is a section on line 11—11 of Figure 4;

Fig. 12 is a section on line 12—12 of Figure 4;

Fig. 13 is a side elevation of the number wheel as viewed from the section line 11—11 of Figure 4 with the gear and pawl plate removed;

Fig. 14 is an elevation of the gear and pawl plate as seen from line 11—11 of Figure 4, the transfer pinion being removed;

Fig. 15 is a view of the opposite side of the gear and pawl plate from that shown in Fig. 14;

Fig. 16 is a perspective view of the main plate 10 or casing member, and

Fig. 17 is a plan view of one of the spacing strips.

In this illustrative construction, I have shown in Figure 1 an improved trip section, generally indicated at 1, which may include any suitable number of number wheels, herein 2, 3, 4 and 5, co-axially arranged and disposed behind the dial 6 of a combined speedometer and odometer in a usual instrument board 7 and adapted to be set by a knob or member 8, this trip section being of an improved construction hereinafter described.

Referring more particularly to the mounting of the trip section 1, it will be noted that as shown in Figure 2, it is carried on a single axial shaft 9, rotatably mounted at its opposite ends in suitable bearings 10, and extending axially through the number wheels 2, 3, 4 and 5. As shown, it also extends through a unit forming main frame 11 which suitably positions the several wheel in fixed positions longitudinally relative to the shaft and is itself suitably positioned in fixed relation to the speedometer casing. Herein, this frame 11 has a disc like end portion 12, adjacent the wheel 2 and is also adapted to be positioned in fixed longitudinal relation to the shaft 9 by a usual spring ring 13 received in a corresponding groove near one end of the shaft 9. Further, this portion 12 has a depending lug 14 slotted to receive any suitable means as, for example, a screw, threaded into a portion 15 stationary on the speedometer frame, to position the frame 11 against rotation or longitudinal movement. As shown, the frame 11 also has a pair of oppositely located, longitudinally extending narrow extensions 16, which extend along on opposite sides of the wheels 2, 3, 4 and 5 and through apertures 17 in a series of spacing or partition plates 18, herein three, disposed between the wheels 2 and 3, 3 and 4, and 4 and 5. It will also be noted that spacing strips 19, herein having series of oppositely located notches 20 in their opposite edges, are disposed in the apertures 17 inside the extensions 16 and that lugs 21 on op-

posite sides of the apertures 17 are disposed in these notches 20. Thus, it will be observed that the several partition plates 18 are positioned by the spacing strips 19, and that the latter and the partition plates are also positioned by the portions 16 of the main frame 11, while the latter is held in position by the spring ring 13, all in such manner as to provide a unitary construction adapted to be held definitely in position and at the same time to be quickly assembled or disassembled as desired.

Referring to the driving and reset operating connections controlled by the knob 8 and operative upon the number wheels 2, 3, 4 and 5, it will be noted that these connections are of a usual type. Herein the driving connections include a gear 25 on the right hand end of the shaft 9, (Fig. 2), adapted to be moved longitudinally into or out of engagement with any suitable co-operating driving gear or pinion 26 driven from any suitable source of power, as for example the wheels of the vehicle or other part moving when the wheels are moving. Herein, this gear 25 rotates as a unit on the shaft 9 with a usual bevel pinion 27 and a usual reciprocable driving sleeve 28 having a conical cam at its end adjacent the wheel 5, and the unit is normally projected over to the right from the full line position shown in Figure 2 by a coaxial coiled spring 29, acting between the member 28 and the first wheel 5, in such manner that the gear 25 is, as usual, normally in mesh with and driven by its driving gear 26. Herein, the operating knob or member 8, which is as usual both reciprocally and rotatably mounted in a suitable support 30, is also provided with a usual conical end 31 adapted upon reciprocation to engage the conical cam on the member 28 and force the latter from its counting or dotted line position, shown in Fig. 2, into its resetting or full line position illustrated therein, while a usual beveled gear 32, rotatable with member 8, meshes with the beveled pinion 27 when the parts are in that position and is thus adapted to rotate the latter gear upon rotation of the member 8. Thus, it will be evident that when the parts are in the dotted line position, shown in Fig. 2, rotation will be imparted to the member 28 from the driving member 26 in such manner that the member 28 and the first wheel 5 will be rotated to effect counting in a usual manner on the associated number wheels, while, when the parts are in the full line position illustrated therein, the driving member 26 will be disconnected and the wheel 5 and its associated wheels may be independently turned thereof upon rotation of the member 8.

Operatively associated with the driving and setting mechanism described is the counting mechanism associated with the wheels 2, 3, 4 and 5 and which is, broadly speaking, operative by the driving member 26 and set by the setting member 8 in a generally well-known manner. Herein, however, this mechanism is, of an improved construction and includes not only an improved structure of the internal transfer pinion type, but also an improved construction including positive locking means for the transfer pinions and improved quick resetting mechanism associated with the wheels and adapted to reset the same while the locking mechanism continues to lock the several units, all in such manner as, while, producing a construction which is very quickly and easily reset, also to produce an exceedingly accurate construction in which there is no chance of splitting a tooth.

Referring first to the counting mechanism, as distinguished from the resetting mechanism, it will be noted that the wheel 5, which as usual in a trip section is graduated to represent tenths of a mile, is provided with a hub portion 35 around which the spring 29 is disposed and which has an abutment 36, against which one end of this spring acts. This hub portion is herein, as preferably, formed integral with the wheel 5 and is also suitably fixed to the non-reciprocable, rotatable shaft 9, as by a pin 37. Sockets 38 are also provided in this hub portion at right angles to the pin in order to permit adjustment of the wheel 5 relative to the shaft during assembly or the like and to receive usual slip driving means such as shown, for example, in the patent to Zubaty 1,783,398, formed in a usual manner on the member 28, and indicated at 38' in Figure 4. As shown the wheel 5 is also disposed outside of the right hand partition plate 18 and carries on its inner face locking mechanism adapted to operate as hereinafter described, with an internal transfer pinion 39 carried by that plate, while said pinion in turn co-operates with a gear and pawl plate 40 on the opposite side of the partition plate 18 and the plate 40 is in turn operatively connected to the second number wheel 4 through improved clutch connections hereinafter described.

Inasmuch as the mechanism from the inside face of the wheel 5 to and including the right hand face of the wheel 4 is the same in each pair of wheels, it is thus necessary only to describe this structure in connection with the single pair of wheels comprising the wheels 5, 4. More particularly, it will be observed that the inner face of the wheel 5 is, as shown in Figures 4 and 6, provided with an annular locking surface or locking ring 41 projecting laterally therefrom toward the partition plate 18 and relatively closely adjacent the periphery of the wheel while providing an open space 41' inside the ring 41, permitting the wheel 5 to rotate freely about the pinion 39. This locking ring is provided with a single tooth aperture 42 which extends through a lateral projection 43 on the surface of ring 41 and is adapted to receive the adjacent end of one of the long teeth 44, herein three in number, on the transfer pinion 39. Thus, during rotation of the wheel 5, the pinion 39 will be locked against rotation save when said aperture 42 is opposite one of the pinion teeth 44, while the wheel 5 at any time may rotate freely about the pinion. As shown herein, the transfer pinion 39 is of a usual mutilated type and has its long teeth 44 extending clear across the same, and also has intermediate shorter teeth 45 on one end provided between corresponding end portions of the teeth 44, while the opposite end portions of the teeth 44, i. e. those portions of the same which engage in the aperture 42, are beveled off at their sides as illustrated.

Herein, this transfer pinion 39 is rotatably mounted on a pin 46 which, in turn, has its end remote from the wheel 5 fixed to an inwardly bent arcuately disposed strip 47 on the adjacent partition plate 18, while this strip is disposed in such manner that the transfer pinion on the pin has its opposite ends accessible from opposite sides of the plate. Here, it will also be noted that the plate 18 is formed of a single thickness of sheet metal and that this strip 47 is struck up therefrom and provided with an intermediate portion 48 parallel to the plane of the plate 18 and spaced therefrom, on which the pin 46 is

fixed, this portion 48 herein being connected to the body of the plate by inclined portions at its opposite ends. Further, it will be noted that the strip 47 is spaced from the periphery of the plate 18 by an arcuate slot 49 and that it is also spaced on its opposite side from the body of the plate by a corresponding but shorter and narrower slot 50 in such manner as to leave a portion of metal 51 surrounding the axial aperture 52 in the partition plate through which the shaft 9 extends.

Operatively associated with the ends of the transfer pinion teeth 44 and 45 which extend through the partition plate 18, is the gear and pawl carrying plate 40 having teeth 53 around its inner periphery and accordingly adapted to be rotated when the transfer pinion is rotated. As shown, this gear and pawl plate 40 is also suitably cut away around its axis, as shown at 54, in such manner as to permit it to house the portion 48 on the partition plate and rotate about the pinion 39. Herein, the same is also provided with a hub portion 55 which extends toward the plate 18 and is rotatable on a corresponding hub portion 56 on that side of the wheel 4. The opposite face of the gear and pawl plate 40, as shown in Figure 15, is also provided with a laterally projecting reduced portion 40', herein substantially oval and having oppositely disposed, generally T-shaped spring retaining slots 57 in its ends. These slots 57 are adapted to receive the bent ends 58 of spring pawl members 59 having bent free ends 60 and two such slots 57 and spring members 59 are preferably provided on the plate 40, the springs herein being oppositely located and extending clockwise, as shown in Figure 15. To facilitate assembly, each slot 57 is also preferably widened at its base to enable it to receive and position the end portion 58 of a spring 59 at either side of the same in reverse positions of the spring. These springs 59, in turn, have their ends 60 received in spaces 61 between teeth 62 on the adjacent face of the wheel 4, ten such spaces and teeth being herein illustrated. Attention is also directed to the fact that these teeth are herein spaced inward or to the left from the right hand edge of plate 40, Fig. 4, in such manner as to permit the latter to be housed within the lateral limits of the wheel 4.

As a result of the provision of this mechanism, it will be evident that when the first wheel 5 is rotated as before described, the transfer pinion 39 will be locked against rotation and accordingly hold the gear and pawl plate 40 against rotation until one of the teeth 44 on the pinion 39 comes opposite the aperture 42 in the locking ring 41. Then, the wheel 5 having made a complete revolution, the transfer pinion 39 will be actuated in such manner as, with the gear 40 and wheel 4 then moving together, to advance the number wheel 4 one tenth of a revolution, i. e. to register in a well-known manner. Similarly, the mechanism being the same between each set of adjacent number wheels, the number wheel 4 will, upon the completion of a complete revolution, actuate the number wheel 3 through a tenth of a revolution and the latter wheel will similarly actuate the wheel 2 in a well-known manner. Thus it will be evident that all of the wheels, through the locking mechanism provided, are locked in such manner as to insure an accurate count when operated.

Referring to the resetting mechanism, it will be noted that the shaft 9 is provided throughout its length with an angled notch 65 and that the

number wheels 4, 3 and 2 each carry pawl mechanism adapted to co-operate with this notch. Inasmuch as the resetting mechanism on each number wheel 2, 3 and 4 is the same, it is sufficient to describe that on wheel 4. More particularly, it will be noted that, as shown in Figure 13, the latter wheel is provided with a longitudinal pawl slot 66 in its hub 56 and also with a substantially segmental pawl aperture 67 opposite this slot. In this aperture 67, a pawl 68 is pivoted at 69 and adapted to move toward and from the surface of the shaft 9, while normally being pressed toward the latter by a spring 70 having a bent end 71 seated in a corresponding slot in the inner face of the wheel 4 at one end of the aperture 67. Further, it will be noted that, by reason of the spring clutch therebetween, the wheel 4 is rotatable relative to its gear 40 which remains stationary by reason of the action of the locking mechanism.

Thus, it will be evident that when the member 8 is pushed in to disconnect the gears 25 and 26, as shown in full lines in Figure 2, and is then rotated to the right (Fig. 2), the shaft 9 will be rotated in a counterclockwise direction (Fig. 3), by reason of its pin connection 31 to the hub 35 of the first wheel 5. As a result, the notch 65 in the shaft will pick up the pawls 68 of the several number wheels 4, 3 and 2, and cause these wheels to be rotated back to zero, the same then rotating relative to the gear and pawl carrying plates 40 which will remain stationary due to the action of the locking mechanism. For example, assuming the initial reading to be 3.9, the tenths wheel will first rotate reversely as shown in Figure 2, or counterclockwise as shown in Figure 13, until it indicates 3, and then the units wheel will be picked up in a usual manner and move with it so that the next indications will be 2.2, 1.1 and 0.0. It will also be evident that all of the wheels 5, 4, 3 and 2, will be reset in a single reverse revolution or less of the shaft 9 and that when the member 8 is released or pulled out to its normal position, shown in dotted lines in Figure 2, the spring 29 will again cause the gears 25 and 26 to be engaged, also as shown in dotted lines, as soon as the beveled pinion 32 disengages the beveled pinion 27 and the cam portion 31 of the member 8 releases the cam 28.

By my improved construction, it is made possible for the number wheels to be rotated relative to their respective gears in such manner as to permit resetting while still utilizing positive locking mechanism. Attention is further directed to the fact that this locking of the several units continues throughout the resetting operation, my improved construction being such that the units continue to be positively locked by their respective locking rings throughout the resetting operation. Further, it will be observed that during resetting, no built up load is present, as is the case when one, two, or three additional springs act additively during the resetting operation. Attention is also directed to the fact that by rotating the member 8 to drive the wheels 5, 4, 3 and 2, it is possible to set the number wheels very conveniently at any predetermined reading. For example, when using a guide book in touring, and coming from a cross road to a place said by the book to be 111.1 miles (or 222.2, 333.3, etc.) from another place and on a route to the latter appearing in the book, it is possible, by rotating the wheels reversely through my improved quick resetting mechanism, to set the same to indicate 111.1 miles or (222.2, 333.3 etc.)

and thereafter check the route to the desired place by comparing the distances given in the guide book with those indicated on the number wheels; for example, turning right at 111.5 miles, 5 when the guide book states that a right turn should be made. Further, where the distance named in the book is more than any number which can be presented by operation of the quick 10 resetting mechanism, as, for example, 125 miles, it will also be evident that the wheels may be very conveniently set for this number by turning them reversely through the quick reset mechanism to the nearest number which can be presented thereby, here 111.1, and then again reversing 15 the direction of rotation of the member 8 until the wheels indicate 125, after which the member 8 may be allowed to return to its normal position.

As a result of my improved construction, it 20 will also be noted that it is made possible to obtain a quick reset of the several units by rotating an axial reset shaft extending there-through, and also to obtain a more slow resetting drive of the units through their transfer mechanism while rotating the same about the axis of 25 this shaft, all while using a longitudinally fixed resetting shaft and thus avoiding the necessity for providing both a reciprocable reset shaft and means for reciprocating the same. It will also 30 be noted that while obtaining these advantages it is also made possible to mount the drive controlling connections reciprocably and rotatably on the shaft and within the longitudinal limits thereof. Thus it is possible to obtain at will from a 35 common actuator, a rotation of the reset shaft to effect a quick reset or the shifting of the drive controlling mechanism longitudinally of the shaft and the subsequent rotation of the units thereby through their transfer mechanism during a slow 40 reset, as, for example, when turning from a reading of 111.1 to 125; all as distinguished from the constructions of the prior art requiring a reciprocable shaft and drive controlling means for reciprocating the shaft disposed beyond the end 45 of the latter, or the use of a stationary stud in lieu of a shaft and incapable of effecting a quick reset, or a selective quick or slow reset. It will also be noted that although in the illustrative construction, the first unit is rotatable with the 50 resetting shaft during quick resetting, all necessity for shifting the shaft longitudinally, or any of the units longitudinally with the shaft is also obviated by my improved construction. These 55 and other advantages of my improved construction will, however, be clearly apparent to those skilled in the art.

While I have in this application specifically described one embodiment which my invention 60 may assume in practice, it will be understood that this form of the same has been described for illustrative purposes, and that the invention may be modified and embodied in various other forms without departing from its spirit or the scope of the appended claims.

65 What I claim as new and desire to secure by Letters Patent is:—

1. In a counter, a plurality of number wheels having a longitudinally fixed axial resetting shaft, internal transfer mechanism between said 70 wheels having positive locking mechanism, driving mechanism for said wheels, and mechanism for disconnecting said driving mechanism and resetting said wheels while said transfer mechanism is locked.

75 2. In a counter, a plurality of number wheels,

internal transfer means therebetween including a transfer pinion, rotatable locking means for said transfer pinion, a longitudinally fixed driving shaft for said wheels, and means for resetting said wheels upon reverse rotation of said shaft while said locking means continues to lock the parts.

3. In a counter, a plurality of coaxial number wheels, internal transfer mechanism therebetween including a transfer pinion and a co-operating locking ring carried by the driving wheel and positively locking said transfer pinion, driving mechanism for said wheels, and mechanism for disconnecting said driving mechanism and resetting said wheels while said pinion is locked by said ring including a longitudinally fixed reset shaft, an actuator, and operative connections selectively operable upon reverse rotations of said actuator for driving said wheels and for rotating said reset shaft to effect 20 a quick reset of said wheels.

4. In a counter, a plurality of number wheels, internal transfer mechanism therebetween including a transfer pinion and gear means co-operating therewith and rotatable with different 25 wheels, holding means for said transfer pinion carried by one of said wheels, and resetting mechanism for the other wheels operative upon rotation of said wheel carrying said holding means including wheel carried reset pawl means 30 and a grooved longitudinally fixed reset shaft reversely rotatable to drive said wheels and pick up said pawl means.

5. In a counter, a plurality of number wheels, internal transfer mechanism therebetween including a transfer pinion and cooperating gear means rotatable with different wheels, a locking ring for positively locking said transfer pinion carried by the driving wheel, a longitudinally fixed driving shaft fixed to said driving wheel, 40 and resetting mechanism operative upon the driven wheel upon reverse rotation of the driving wheel and while said locking mechanism remains locked.

6. In a counter, a plurality of number wheels, internal transfer means therebetween including a transfer pinion, gears rotatable with different 45 wheels, locking means for said pinion, and combined driving and resetting mechanism including a clutch between one of said wheels and the gear carried thereby and a longitudinally fixed combined driving and resetting shaft reversely operable during driving and resetting and connecting or disconnecting said clutch.

7. In a counter, a plurality of number wheels, internal transfer means therebetween including a transfer pinion, gears rotatable with different 55 wheels, and locking means for said pinion, and combined driving and resetting mechanism including ratchet means between one of said 60 wheels and a gear carried thereby permitting relative rotation between said wheel and gear during resetting and a longitudinally fixed combined driving and resetting shaft reversely operable during driving and resetting and connecting or disconnecting said elements.

8. In a counter, a plurality of counter wheels, internal transfer means therebetween including a transfer pinion, gears rotatable with different 70 wheels, and locking means for said pinion, and resetting mechanism including a clutch between one of said wheels and a gear normally rotatable with the latter, and means for effecting relative rotation between said wheel and said gear 75

- including a longitudinally fixed resetting shaft fixed to the other wheel.
9. In a counter, a plurality of driving and driven counter wheels, internal transfer means therebetween including a transfer pinion, gears rotatable with different wheels, and locking means for said pinion, and resetting mechanism including a clutch between the driven wheel and a gear normally rotatable with the latter, pick up means carried by said driven gear, and a longitudinally fixed reversely rotatable driving and resetting shaft fixed to said driving wheel.
10. In a counter, a plurality of counter wheels, internal transfer means therebetween including a transfer pinion, gears rotatable with different units, and locking means for said pinion, and resetting mechanism including a clutch between one of said wheels and the gear carried thereby, a longitudinally fixed reset shaft extending through said units and driving the driving wheel, and pick up pawl means for the driven wheel operative upon reverse rotation of said shaft.
11. In a counter, coaxial driving and driven number wheels, a partition plate therebetween, a transfer pinion mounted in said partition plate, a locking ring having transfer aperture means therein cooperating with said pinion and carried by the driving wheel, a gear plate on the opposite side of said partition plate likewise cooperating with said pinion, a clutch between said gear plate and driven number wheel permitting relative rotation between the same and said gear, a longitudinally fixed shaft driving said wheels when rotated in one direction, and resetting means for said wheels operable upon reverse rotation of said shaft.
12. In a counter, coaxial driving and driven number wheels, a partition plate therebetween, a transfer pinion mounted in said partition plate, a locking ring having tooth aperture means therein cooperating with said pinion and carried by the driving wheel, a gear plate on the opposite side of said partition plate likewise cooperating with said pinion, spring pawl means carried by said gear plate, cooperating tooth means carried by said driven number wheel, a longitudinally fixed reset shaft driving said wheels when rotating in one direction, and resetting means for said wheels operative upon reverse rotation of said shaft.
13. In a counter, coaxial driving and driven number wheels, a partition plate therebetween, a transfer pinion mounted in said partition plate, a locking ring having tooth aperture means therein and cooperating with said pinion carried by the driving wheel, a gear plate on the opposite side of said partition plate likewise cooperating with said pinion, spring ratchet means between said gear plate and said driven wheel, and resetting means for said number wheels including a longitudinally fixed shaft fixed to said driving wheel and having a resetting aperture in said shaft, and pawl means carried by said driven wheel engageable in said aperture when the shaft is rotated in one direction.
14. In a counter, coaxial driving and driven number wheels, a partition plate therebetween, a transfer pinion mounted in said partition plate, a locking ring having tooth aperture means therein and cooperating with said pinion carried by the driving wheel, a gear plate on the opposite side of said partition plate likewise cooperating with said pinion, spring ratchet means between
- said gear plate and said driven number wheel, and resetting means for said number wheels including a longitudinally fixed shaft fixed to said driving wheel and having a resetting aperture in said shaft, and pawl means carried by said driven wheel engageable in said aperture when the shaft is rotated in one direction, said gear plate and said driven number wheel, and resetting means for said number wheels including a longitudinally fixed shaft fixed to said driving wheel and having a resetting aperture in said shaft, and pawl means carried by said driven wheel engageable in said aperture when the shaft is rotated in one direction, means for rotating said shaft in one direction, and manually adjustable means for disconnecting said means and rotating said shaft in opposite directions.
15. In a trip section for odometers, a plurality of counter wheels, internal transfer mechanism therebetween having positive locking means, driving means for the driving wheel, means for disconnecting the latter from said driving means and rotating the same while disconnected including a longitudinally fixed resetting shaft, and cooperating resetting mechanism operative by said shaft for resetting all of said wheels while said transfer mechanism is locked.
16. In a trip section for odometers, a plurality of counter wheels, internal transfer mechanism therebetween having positive locking means, driving means including a reset shaft, means within the longitudinal limits of said shaft for disconnecting said shaft from said driving means and rotating said wheels in opposite directions while disconnected, and cooperating resetting mechanism operative upon rotation in one direction for resetting said wheels while said transfer mechanism is locked.
17. In a trip section for odometers, a plurality of counter wheels, internal transfer mechanism therebetween having positive locking means, a rotatable combined driving and resetting shaft, means within the longitudinal limits of said shaft operable thereby upon rotation of the latter in opposite directions for driving and resetting said wheels, means for driving said shaft, and means for selectively connecting and disconnecting said shaft and said driving means.
18. In a trip section for odometers, a plurality of counter wheels, internal transfer mechanism therebetween having positive locking means, a rotatable combined driving and resetting shaft fixed against longitudinal movement, means operable thereby upon rotation of the latter in opposite directions for driving and resetting said wheels, means for driving said shaft, and means for selectively connecting and disconnecting said shaft and said driving means, said last mentioned means being rotatable reversely to rotate said wheels in a forward or reverse direction when said shaft is disconnected from said driving means.
19. In a trip section for odometers, a plurality of counter wheels, internal transfer mechanism therebetween having positive locking mechanism, driving means for the driving wheel, means for disconnecting said driving means and rotating the driving wheel in opposite directions while disconnected from said driving means including a longitudinally fixed shaft rotatable with said driving wheel, and cooperating resetting mechanism cooperating with each of the wheels other than the driving wheel for effecting resetting of said other wheels during a single revolution of said shaft while said driving means is disconnected and said transfer mechanism remains locked.
20. In a trip section for odometers, a plurality of counter wheels, internal transfer mechanism therebetween having means for positively locking said mechanism, driving means for the driving wheel, means for disconnecting said driving means and rotating the driving wheel in either

- direction while disconnected from said driving means including a longitudinally fixed shaft rotatable with said driving wheel, and co-operating resetting mechanism cooperating with 5 each of the wheels other than the driving wheel operative while said transfer mechanisms are locked and having a non-reversible ratchet between each of said other wheels and the transfer mechanism connecting said wheel to the 10 adjacent wheel of lower order, and also wheel pick-up means for each of said other wheels operative when said driving wheel is rotated in one direction.
21. A trip section for odometers or the like comprising number units having transfer mechanism therebetween, quick reset means for picking up a plurality of said units and returning them to zero having a reset shaft, a driving element for said units shiftable longitudinally relative to said 15 shaft to disconnect the drive thereof, a reciprocable and oppositely rotatable actuating member, means operative upon reciprocation of said member for shifting said element as aforesaid, and means selectively operable by said member upon 20 rotation thereof in opposite directions for effecting driving of said units through said driving element or a quick reset of said units through said reset shaft.
22. A trip section for odometers or the like comprising number units having transfer mechanism therebetween, quick reset means for a plurality of said units comprising reset pawls thereon and a reset shaft having means cooperating with said pawls to pick up said units, a spring pressed 25 clutch member movable longitudinally relative to said shaft to tension its spring and disconnect said units from the drive thereof, a reciprocable and rotatable actuating member, means for shifting said clutch member as aforesaid upon reciprocation of said actuating member, and means selectively operable by rotation of said actuating member in opposite directions for effecting a quick 30 reset of said units through said pawls and reset shaft or rotation of said units through said clutch 35 member and said transfer mechanism.
23. A trip section for odometers or the like comprising number units having transfer mechanism therebetween, quick reset means for a plurality of said units having reset pawls thereon and a reset shaft having means cooperating with said pawls to pick up said units, a clutch member movable longitudinally relative to said shaft to disconnect said units from the drive thereof, a reciprocable and rotatable actuating member, means for shifting said clutch member as aforesaid upon reciprocation of said reset member, and means selectively operable upon opposite 40 rotations of the latter following clutch shifting for rotating said reset shaft in one direction to drive said units from said shaft through said transfer mechanism and in the opposite direction to drive said reset shaft to pick up said pawls and reset said units.
24. A trip section for odometers or the like comprising number units having transfer mechanism therebetween, quick reset means for picking up a plurality of said units and returning them to zero having a longitudinally fixed reset shaft, a driving 45 element for said units shiftable longitudinally relative to said shaft to disconnect the drive thereof, a reciprocable and oppositely rotatable actuating member, means operative upon reciprocation of said member for shifting said element as aforesaid, and means selectively operable by said mem- 50
- ber upon rotation thereof in opposite directions for effecting driving of said units through said driving element or a quick reset of said units through said reset shaft.
25. In a counter unit, a series of operatively connected number wheels having partition plates therebetween and projecting spaced lugs on said partition plates, spacing strip means interlocked with said lugs, and a frame having portions positioning said spacing means and said plates 55 through said lugs.
26. In a counter unit, a series of operatively connected number wheels having partition plates therebetween and oppositely projecting spaced lugs on said partition plates, spacing strip means interlocked with said lugs, a frame positioning 15 said spacing means and said plates, said frame having extensions extending longitudinally of said wheels between the spaced lugs on said plates, and means for fixing said frame relative to said 20 wheels permitting longitudinal withdrawal of said frame at will.
27. In a counter unit, a series of operatively connected number wheels having partition plates therebetween and projecting spaced lugs on said partition plates, spacing strips having notched edges interlocked with said lugs and connecting said wheels and plates into a unit, and a frame receiving said unit longitudinally and having portions extending between said 25 spaced lugs externally of said spacing means.
28. In a counter unit, a series of operatively connected number wheels having partition plates therebetween and a protruding shaft, means interlocked with said plates operatively connecting said wheels and plates into a unit, a frame having means receiving said unit longitudinally and interlocked with said partition plates to inhibit rotation of said unit while permitting longitudinal separation, and removable means connecting said frame to said shaft while enabling 30 longitudinal separation at will.
29. In a counter unit, a series of operatively connected number wheels having partition plates therebetween and a protruding shaft, means 35 connecting said wheels and plates into a unit, a frame having an open end receiving said unit longitudinally therein and a closed end through which said shaft projects, means for inhibiting rotation of said unit in said frame while permitting longitudinal separation, and removable means for connecting said unit and frame against longitudinal separation.
30. A partition device for internal transfer type counters comprising a single plate having a laterally deflected struck up strip connected at both ends to said plate and providing a transfer pinion pin seat between its ends, a pin carried on said seat perpendicularly to said plate and projecting on opposite sides of the latter, 40 and a transfer pinion rotatable on said pin and having its opposite ends accessible from opposite sides of said plate.
31. A partition device for internal transfer type counters comprising a single plate having a laterally deflected struck up strip connected at both ends to said plate and providing a transfer pinion pin seat between its ends, said struck up strip being arcuately disposed and spaced 45 from the periphery of said plate by an arcuate slot and also having a slot between said struck up strip and the axis of said plate.
